Primary Examiner — Paula Greene(74) *Attorney, Agent, or Firm* — Adam R. Stephenson, Ltd.(57) **CLAIM**

The ornamental design for over ear headphone, as shown and described.

DESCRIPTION

FIG. 1 is front perspective view of an embodiment of over ear headphone;

FIG. 2 is a front view thereof;

FIG. 3 is rear view thereof;

FIG. 4 is a left side view thereof;

FIG. 5 is a right side view thereof;

FIG. 6 is a top view thereof; and,

FIG. 7 is a bottom view thereof.

All broken lines represent unclaimed features of the article to which the design is applied.
